UNITED STATES PATENT OFFICE.

RUBEN B. LAWRENCE, OF BELLEVUE, PENNSYLVANIA, ASSIGNOR TO FEDERAL LABORATORIES, INCORPORATED, OF PITTSBURGH, PENNSYLVANIA, A CORPORATION OF DELAWARE.

DEVICE FOR PREVENTING ROBBERIES.

Application filed February 24, 1922. Serial No. 539,042.

To all whom it may concern:

Be it known that I, RUBEN B. LAWRENCE, a citizen of the United States, residing at Bellevue, county of Allegheny, Pennsylvania, have invented a new and useful Improvement in Devices for Preventing Robberies, of which the following is a full, clear, and exact description.

The present invention relates to a device for preventing robberies and more particularly to a device for producing an incapacitating gas. The gas is contained in a receptacle which also contains a detonating charge and an electric igniter. The receptacle preferably resembles an electric lamp bulb or other usual room fixture, so that it will be inconspicuous. The receptacle is preferably provided with a base which allows it to be removably placed in a standard electric lamp socket.

In the drawings which illustrate the preferred embodiment of the invention,

Figure 1 is a side elevation of the preferred embodiment of the device as it appears inserted in a lighting socket;

Figure 2 is a sectional view, and

Figure 3 is a wiring diagram.

Referring to the illustrated embodiment of the invention, a glass receptacle 1 contains a glass container or containers 2 shown in the form of vials which contain a gas forming liquid 3. The vials are hermetically sealed. The receptacle 2 also encloses a detonator 4, located between the vials 3. Plaster of Paris or body of similar material 5 is used to hold the vials and detonator in position.

The receptacle 1 is made in the form of the ordinary electric lamp bulb and is either frosted or made of milk white glass to conceal its contents. It is provided with a standard electric lamp base 6 which screws into the usual electric lamp socket 7 and makes electrical connection therewith. The detonator 4 is of usual construction and contains a detonating or explosive charge 8 and an electric igniter 9. The wires 10 from the igniter are connected to the base of the receptacle so as to make electric connection with the socket 7.

The vials 2 contain a substance which will produce an incapacitating gas, preferably

a gas which will completely incapacitate for a short time but which will not leave any permanent after effects. The usual 55 lachrymose, sneeze, or vomiting gases, or a combination of them, may be used. The gas forming liquid known as dibrombenzine, which is a lachrymose gas, is preferably employed as it will completely but temporarily incapacitate a person.

A bank or other place which is to be protected against robbery is wired and the lighting sockets placed in their proper places. This work may be done by the 65 ordinary electricians who will not know for what purpose the wiring is to be put in. The gas and detonating charge holding receptacles which look exactly like electric lights may then be put in place, without any outsider knowing that the bank 70 is so protected.

In Figure 3 is illustrated diagrammatically the electric wiring. A number of the gas containing receptacles are shown as 75 inserted in the lamp sockets 7 which are connected to an electric circuit 11 containing a battery 12 and a number of switches preferably in the form of push buttons 13. The push buttons 13 may be placed in any convenient places where any one of a number 80 of employees can readily reach them in case of an attempted robbery.

When one of the push buttons is pressed the detonating charges explode with a loud 85 report which will attract the attention of the would-be robbers from their burglarious designs, giving the employees a chance to drop behind counters or other protections and to seize gas masks. The detonating 90 report will be immediately followed by the incapacitating vapors from the gas producing substance. The detonating charge will completely shatter the gas containers and will atomize the liquid insuring a quick 95 and thorough distribution thereof. Only a small amount of the liquid is needed as these gas producing liquids are now developed where a fraction of an ounce will incapacitate all persons in an ordinary size 100 room.

While I have specifically illustrated and described the preferred embodiment of my invention, it will be understood that the

invention is not limited to all of the illustrated and described details, but may be otherwise embodied within the scope of the following claims.

5. I claim:

1. A robbery preventing device comprising a receptacle containing an incapacitating gas producing substance, a detonating charge adapted to shatter the receptacle and an electric igniter for the detonating charge, and having a base adapted to fit and make electric connection with a standard electric lamp socket, substantially as described.
10. 2. A robbery preventing device comprising a receptacle resembling an electric lamp bulb in appearance and containing an incapacitating gas producing substance, a detonating charge adapted to shatter the receptacle and an electric igniter for the detonating charge, and having a base adapted to fit and make electric connection with the usual electric lamp socket, substantially as described.
15. 3. A robbery preventing device comprising a frangible container having therein an incapacitating gas producing substance and also containing a detonating charge adapted to rupture the container and scatter the gas producing substance, the gas producing substance substantially surrounding the detonating charge in the container, substantially as described.
20. 4. A robbery preventing device comprising a glass container having therein an incapacitating gas producing substance and also containing a detonating charge adapted to rupture the container and scatter the gas producing substance, the gas producing substance lying between the detonating charge

and the walls of the container, substantially as described.

5. A robbery preventing device comprising a frangible container resembling a room fixture and having therein an incapacitating gas producing substance, and also containing a detonating charge adapted to rupture the container and scatter the gas producing substance, the gas producing substance surrounding the detonating charge in the container, substantially as described.

6. A robbery preventing device comprising a frangible container having therein an incapacitating gas producing substance and also containing a detonating charge adapted to rupture the container and scatter the gas producing substance, the gas producing substance surrounding the detonating charge in the container, and a glass separating wall between the detonator and the gas producing substance, substantially as described.

7. A robbery preventing device comprising an outer container, a detonating charge therein, and a gas producing substance in a separate container lying within the outer container between the detonating charge and the wall of the outer container, substantially as described.

8. A robbery preventing device comprising an outer container, a detonating charge contained therein, a plurality of separate containers within the outer container, each containing a gas producing substance, the inner container lying between the detonating charge and the walls of the outer container, substantially as described.

In testimony whereof I have hereunto set my hand.

RUBEN B. LAWRENCE.
